UNITED STATES PATENT OFFICE.

JOHN A. LESOURD AND JAMES LOTAN, OF PORTLAND, OREGON.

ELEVATOR FOR COAL AND OTHER SUBSTANCES.

SPECIFICATION forming part of Letters Patent No. 299,656, dated June 3, 1884.

Application filed October 17, 1883. (No model.)

To all whom it may concern:

Be it known that we, JOHN A. LESOURD and JAMES LOTAN, both of Portland, in the county of Multnomah and State of Oregon, 5 have invented certain new and useful Improvements in Coal and other Elevators, of which the following is a full, clear, and exact description.

This invention more especially relates to 10 elevators for discharging coal and other substances, but more particularly coal, from the holds of vessels and barges, and has for its object the taking of the material to be discharged from the ship's hold or barge and 15 raising it uninterruptedly and continuously to a suitable height by means of an endless chain provided with buckets to admit of its being run when dumped into any desired receptacle—as, for instance, in the case of coal 20 into the bins of bunkers of warehouses.

The invention consists in an elevator of this description having combined with it one or more hydraulic or other rams for raising it, and an engine or engines carried by the ram 25 or rams for working the endless chain of buckets, and in certain constructions and combinations of details and devices for adjusting and holding the endless chain of buckets in 30 position, and for facilitating the general operation of the elevator, substantially as hereinafter described.

An elevator constructed in accordance with 35 this invention will unload and deliver, as required, an entire ship's cargo of coal in a very brief space of time and with great economy.

Reference is to be had to the accompanying drawings, forming part of this specification, in which similar letters of reference indicate 40 corresponding parts in all the figures.

Figure 1 represents a side elevation of our improved elevator applied to a barge, shown in transverse section, and in position for delivering coal taken from the barge at a suitable height into a coal-carrier for distribution 45 within a series of bins. Fig. 2 is a broken front view of the elevator in part; Fig. 3, a broken side view thereof; and Fig. 4, a sectional elevation, upon a larger scale, of the cylinder and valve of one of the engines used to 50 work the endless chain of buckets.

A is the endless chain of buckets *b*, arranged to pass up and down on the outside of a frame, B, having at its upper and lower ends drums

C C', around which the chain travels. The lower drum, C', is a freely-moving one, and 55 is rotated by the travel of the chain around it, while the upper drum, C, gives motion to the chain, said upper drum being mounted on a shaft, *c*, on which are secured, upon each side of the drum, spur-gears *d d*, that are rotated and driven by pinions *e e* on a cross-shaft, *f*, of two engines, D D. Friction-pulleys or other driving devices may be substituted for the toothed gears *d d* and *e e*. The shafts of the drums C C' are set in adjustable 60 boxes *g g* at the upper and lower ends of the frame B, which is stiffened, and strength and compactness insured, by iron frames E E', inserted within the main frame B, which may be of wood. These iron frames serve to bind, 65 support, and hold together the different movable or working parts. The sides of the upper one, E, of these metallic frames are constructed, as shown in Figs. 2 and 3, with outside uprights, *h h*, and serve to carry the trunnions *i i* of the engines D D, which are preferably and are shown as oscillating ones. 70

The whole structure so far, including the frame B, with its drums C C', endless chain A of buckets, and engines D D, is carried 75 by a strong cross rock-shaft, F, which has its bearings in and is supported upon the tops of two hydraulic rams, G G, on either side of the elevator. This manner of supporting the endless chain of buckets, with its driving appliances and connections, provides for swinging or maneuvering the endless-chain carrier A so as to bring its foot over or in line with the ship's hatchways or the hold of the barge 80 H to be unloaded, and also provides for moving the foot of the endless-chain carrier away 85 therefrom when required.

The engines D D, which serve to give motion to the cross-shaft *f* by means of cranks *k k*, set at right angles with each other on the 90 ends of said shaft, it is proposed to operate by water-pressure, although steam, which, however, would be objectionable on account of condensation, might be used. They are stopped and started and their speed regulated, 95 as required, by hand-screws *l l*, arranged to actuate link-and-yoke connections *m m*, applied to their valves, which it is proposed to make of a double-piston balance-slide construction, as shown in Fig. 4, where I represents the piston of one of the engines, and J J the valve 100

fast on a stem, *n*, and arranged to control inlets *o o* and exhaust-ports *p p* to and from the engine-cylinder. Water to drive the engine is admitted between the heads of the valve of either engine by rubber pipes *r*, arranged to connect with the center of the valve-boxes, and the exhaust or waste water is carried off by similar flexible connections, *s*, having branches extending to the upper and lower ends of the valve-boxes. These rubber or flexible connections adapt themselves to the oscillating motions of the engines. The inlet connections *r* are connected with lower receiving-boxes *K* by telescoping pipes *R*, having stuffing-boxes *t* to prevent leakage of the water under pressure, branches *u* from a hydraulic main or force-pump serving to conduct the water to said boxes. The outlet-connections *s* are also attached to telescoping waste-pipes *S* for carrying off the exhaust water from the engines and disposing of it as most convenient.

The hydraulic rams *G G*, which serve to raise and lower the endless chain *A* of buckets, with its operating-engines *D D* and connections, may be either of a single or multiple description, and have any number of stuffing-boxes *v*. For a considerable lift, they should be of a multiple construction. Said rams are connected below with the receiving-boxes *K*, and may have the usual valves and connections of hydraulic elevators. In cases where the necessary amount of lift is limited, then ordinary or single hydraulic jacks may be used in place of the multiple hydraulic ones.

The operation is as follows: The vessel or barge to be unloaded having been made fast, water from the hydraulic main or force-pump is admitted to the hydraulic jack or ram or rams *G G*, to raise bodily the endless chain *A* of buckets, with its engines and other connections or appliances, to admit of the foot of said endless-chain carrier being swung on or by the rock-shaft *F* clear of the ship's rail and over the hatchway or hold of the vessel. The rams *G G* are then operated to lower the endless-chain carrier *A* down into the hold of the vessel, as shown in Fig. 1, after which the engines *D D* are started to lift and discharge, in a continuous or uninterrupted manner, the coal from the barge or vessel. When the coal reaches the top of the elevator, it may be delivered into a chute, *a'*, and from thence pass into a carrier at *b'*, and be distributed and discharged within bins *c'*, having screenings-receivers *d'* below them; or it may be taken from the elevator and dumped in any other way and place or places, as desired. This uninterrupted discharging operation is continued until the vessel is unloaded, after which the endless chain *A* of buckets may be raised by the rams *G G* out of the hold and be swung back to its normal position within a tower, *L*, until wanted again.

65 Tackle may be used for swinging or adjusting and holding the endless-chain elevating or discharging device *A* into position from the

shaft *F* as a center of motion, as described; but it is preferred to use a hydraulic maneuvering ram or jack, *M N*, set nearly horizontal, and connected at its outer end with the lower portion of the frame *B* of the endless chain *A* of buckets, as such contrivance will afford every facility for pushing the foot of the elevator on board ship and holding it there during the operation of discharging the cargo.

If desired, steam or other impelling agent may be used in the place of water under pressure for raising the elevator proper or traveling endless chain of buckets.

Having thus described our invention, what we claim as new, and desire to secure by Letters Patent, is—

1. In coal and other elevators, the combination of an endless chain of buckets, a laterally-swinging frame carrying the same, and one or more raising and lowering rams or jacks, on which said swinging frame is mounted, essentially as and for the purposes herein set forth.

2. In coal and other elevators, the combination, with one or more raising and lowering rams or jacks, of an endless chain of buckets, a laterally-swinging frame carrying said chain, and one or more engines, with mechanism for operating the chain, all mounted on or carried by the raising and lowering ram or rams, substantially as herein described.

3. The combination of one or more raising and lowering hydraulic jacks or rams, one or more hydraulic engines carried by said jacks or rams, and a laterally adjustable or swinging endless chain and bucket elevator arranged for operation by said engine or engines, substantially as specified.

4. The combination of the hydraulic jacks or rams *G G*, the intermediately-arranged endless chain *A* of buckets, with its drums *C C'* and frame *B*, the cross shaft *F*, and the engines *D D*, with mechanism for driving the upper drum of the chain, essentially as described.

5. The combination, with the laterally adjustable or swinging frame *B* and endless chain *A* of buckets, with its drums *C C'*, of the metallic frames *E E'*, the engines *D D*, carried by the one of said frames, and the rock-shaft *F*, on or by which the whole are carried, substantially as specified.

6. The telescoping inlet and outlet pipes *R S* and their flexible connections *r s*, in combination with the raising and lowering jacks or rams *G G* and the engines *D D*, and laterally adjustable or swinging endless chain and bucket elevator carried by said jacks or rams, essentially as described.

7. The maneuvering-ram *M N*, in combination with the laterally-swinging endless chain and bucket elevator, and one or more raising and lowering rams, on which said elevator is mounted, substantially as specified.

JOHN A. LESOURD.
JAMES LOTAN.
